UNITED STATES PATENT OFFICE.

JAKOB MEZGER, OF ST. GALLEN, SWITZERLAND, ASSIGNOR TO THE FIRM GEBRÜDER BÜHLER, OF UZWIL, SWITZERLAND.

DESIGN FOR A CASING FOR A ROLLING MILL.

Application filed October 17, 1924. Serial No. 11,098. Term of patent 14 years.

To all whom it may concern:

Be it known that I, JAKOB MEZGER, a citizen of the Republic of Switzerland, residing at Hebelstrasse No. 12, St. Gallen, Switzerland, have invented a new, original, and ornamental Design for Casing for a Rolling Mill, of which the following is a specification, reference being had therein to the accompanying drawing, forming part thereof.

The figure is a perspective elevation view of a casing for a rolling mill, showing my new design.

I claim:

The ornamental design for a casing for a rolling mill, as shown.

In testimony whereof I affix my signature.

JAKOB MEZGER.
